ROLL PAPER FIXTURE

Samuel N. Hope, Wauwatosa, and Paul Drath, West Allis, Wis., assignors to Griffith-Hope Company, West Allis, Wis., a corporation of Wisconsin

Application October 24, 1932, Serial No. 639,224

3 Claims. (Cl. 242—55.5)

The invention relates to fixtures for dispensing sheets from rolls of paper or the like, such as wax paper, and has for an object the provision of a durable but inexpensive roll-supporting fixture adapted for household use and having a cutting member including a cutting portion extending along the roll and releasably held in operative position with respect to the roll, the cutting member being readily displaceable from its operative position to facilitate replacement of the roll.

The invention further consists in the several features hereinafter described and claimed.

In the accompanying drawing;

Fig. 1 is a top plan view of a roll paper fixture embodying the invention;

Fig. 2 is a transverse sectional view of the fixture taken along the line 2—2 of Fig. 1;

Fig. 3 is a front elevation of one end of the fixture;

Fig. 4 is a fragmentary sectional view taken along the line 4—4 of Fig. 2, and

Fig. 5 is a fragmentary rear view of one end of the fixture, parts being broken away and parts being shown in section.

In this drawing, 10 designates a rectangular base member having marginal flanges 11 which are adapted to engage a support 12, here shown to be a vertical wall. The base member 10 is preferably a sheet metal stamping and is secured to the support 12 by screws 13 which pass through openings 14.

The base member 10 has formed therein near each end a pair of parallel guide slots 16 slidably receiving therethrough the spaced legs of a U-shaped sheet metal strap or stirrup 17, the free ends of the legs projecting forwardly from the base member. A pair of sheet metal roll-supporting arms or brackets 18 have end portions 40 interposed between the spaced legs of the respective straps 17, and each has inturned side flanges 19 which engage embossments 20 formed on the strap legs and which are pivotally connected thereto by rivets 21. Near the rivets 21, the flanges 19 have their edges fulcrumed on ribs 23 embossed on the base member 10 between the slots 16 and the adjacent end edges of the base member.

Each strap or stirrup 17 is urged inwardly by an arched leaf spring 24 which has an intermediate portion bearing on the inner face of the base member and reduced end portions or tongues 25 slidably fitting in openings 26 formed in the strap, thus retaining the spring in place. By this means the arms or brackets 18 are spring-

urged toward each other about their pivotal bearing on the ribs 23.

The above described spring mounting of the arms or brackets is disclosed in the application of Samuel N. Hope and Nicholas Tuszyński for Roll towel fixtures, Serial No. 621,361, filed July 8, 1932.

At their free end portions the arms or brackets 18 are provided with rounded embossments 27 which are adapted to enter the opposite hollow ends of a roll 28 of sheet material to be dispensed, such as wax paper, the roll being rotatably mounted on these embossments. In the present instance, the roll is shown to be provided with a tubular core 29 of paper or other suitable material. An annular shoulder 30 surrounding each embossment 27 is engageable with the end of the roll and is here shown to engage the end of the core. The shoulder 30 is urged against the end of the roll by the action of the spring 24 to frictionally retard the rotation of the roll. In the present instance the embossment 27 and shoulder 30 are formed on a sheet metal cup 27' which has a flaring edge 30' fitting within the outer end of the arm 18 and secured thereto by an inturned marginal bead-forming flange 18' on the arm. With this construction the embossments 27 on the cups may be economically formed in various sizes.

An embossed sheet metal cutting frame 32, formed from a rectangular loop-shaped blank, is pivotally mounted at its rear bar near the lower edge of the base member 10 about an axis parallel to the roll 28, spaced ears 33 being struck up from the base member and pivotally connected to ears 34 bent up from the cutting frame, as by a rod 35 or other suitable means. The cutting frame includes resilient hook-shaped side bars 36 which at their outer ends extend partially around the rounded outer ends of the brackets 18, the side bars 36 being retained by their spring tension against the brackets. The side bars 36 are suitably ribbed to provide the desired degree of resiliency. At their forward free ends the side bars 36 are integrally connected by an outwardly offset longitudinally ribbed cutting bar 37 of arcuate cross-section extending parallel to the roll and having a lower serrated cutting edge 38 spaced from the outer surface of the roll. The upper rear edge of the cutting bar has an intermediate recess 39 to facilitate manual rotation of the roll. The cutting frame 32 can be sprung off the roll-supporting brackets 18 and dropped away from the brackets to the dotted line position shown in Fig. 2, the downward movement

of the frame being limited by the engagement of the rear edge of the frame with the lower edges of the ears 33.

When the roll is to be mounted on the fixture, 5 the cutting frame 32 is placed in the dotted line position of Fig. 2, and one or both of the brackets 18 are moved outwardly against the action of their springs, as indicated by dotted lines in Fig. 1, to permit entrance of the roll between the brackets. The embossments 27 of the spring-urged 10 brackets are then permitted to enter the opposite ends of the roll core. The cutting frame 32 is then swung upwardly and sprung unto the outer ends of the brackets 18.

When the fixture is in use, a length of waxed 15 paper is drawn from the roll 28 through the space between the side bars 36 and is cut off by lifting it against the serrated cutting edge 38. The roll is prevented from turning too freely by the frictional engagement of the brackets 18 with the 20 roll. The resilient mounting of the arms 18 permits the roll to be properly accommodated on the fixture notwithstanding variations in roll width met with in manufacture. When the roll is exhausted, the core can be easily removed from 25 the fixture and another roll mounted in place, as above described.

The fixture is constructed of relatively few 30 parts which are principally sheet metal stampings, thereby permitting economical manufacture.

What we claim as new and desire to secure by Letters Patent is:

1. A fixture for paper rolls and the like, com-

prising a support having spaced roll-carrying brackets for receiving a rotatable roll therebetween, and a cutting member swingably mounted on said support and having a cutting portion extending along the roll, said cutting member having resilient hooked side bars connected to said cutting portion and adapted to be releasably sprung over and embrace the outer ends of said brackets for retaining said cutting portion along the roll.

2. A fixture for paper rolls and the like, comprising a support having spaced brackets for rotatably carrying a roll therebetween, and a sheet metal cutting frame having a pivotal mounting on said support spaced from the roll axis to be swung thereon into and out of operative position with respect to the roll, said cutting frame having a cutting portion for disposition along the roll and having resilient hooked side portions at opposite ends of said cutting portion to be sprung over and into latching engagement with the outer ends of said brackets when said frame is swung about its pivotal mounting to its operative position.

3. A cutting device for a fixture rotatably supporting a paper roll or the like, comprising a resilient sheet metal frame having a cutting bar and resilient side bars integral therewith, the portions of said side bars adjacent said cutting bar being reversely hooked to form a resilient latching means, and the portion of said frame distant from said cutting bar having a pivotal mounting.
